(57) **CLAIM**

The ornamental design for an LED light panel, as shown and described.

DESCRIPTION

FIG. 1 is a front elevation view of an embodiment of an LED light panel showing the new design;

FIG. 2 is a front perspective view thereof;

FIG. 3 is a side elevation view thereof, the opposing side elevation view being a mirror image thereof;

FIG. 4 is a top plan view thereof;

FIG. 5 is a bottom plan view thereof; and

FIG. 6 is a rear elevation view thereof.

FIG. 7 is a front elevation view of another embodiment of an LED light panel showing the new design;

FIG. 8 is a front perspective view thereof;

FIG. 9 is a side elevation view thereof, the opposing side elevation view being a mirror image thereof;

FIG. 10 is a top plan view thereof;

FIG. 11 is a bottom plan view thereof; and

FIG. 12 is a rear elevation view thereof.

FIG. 13 is a front elevation view of yet embodiment of an LED LIGHT PANEL showing the new design;

FIG. 14 is a front perspective view thereof;

FIG. 15 is a side elevation view thereof, the opposing side elevation view being a mirror image thereof;

FIG. 16 is a top plan view thereof;

FIG. 17 is a bottom plan view thereof; and

FIG. 18 is a rear elevation view thereof.

The broken lines depict features of the LED light panel that form no part of the claimed design.
